UNITED STATES PATENT OFFICE.

FREDERICK C. OVERBURY, OF NEW YORK, N. Y., ASSIGNOR TO FLINTKOTE MANUFACTURING COMPANY, OF RUTHERFORD, NEW JERSEY, A CORPORATION OF NEW JERSEY.

METHOD OF MAKING SHINGLE-STRIPS AND BLANKS THEREFOR.

No. 908,125.

Specification of Letters Patent.

Patented Dec. 29, 1908.

Application filed August 15, 1907. Serial No. 388,721.

To all whom it may concern:

Be it known that I, FREDERICK C. OVERBURY, of New York, in the county of New York and State of New York, have invented 5 certain new and useful Improvements in Methods of Making Shingle-Strips and Blanks Therefor, of which the following is a specification.

This invention relates to roofing strips 10 composed of flexible waterproof material, and adapted to be laid in overlapping courses, each strip constituting a member of the covering of a roof or other surface of a building.

15 The invention has for its object to provide a roofing strip or member which, when assembled with other strips, will have a continuous edge and a notched or slotted edge, the latter resembling a strip or row of 20 shingles.

The invention consists in the improved method of making shingle strips, and in a shingle strip blank produced in practicing said method, all as hereinafter described.

25 Of the accompanying drawings, forming a part of this specification,—Figure 1 represents a side view of a portion of my improved shingle strip blank. Fig. 2 represents a view showing the blank illustrated in Fig. 1, 30 longitudinally subdivided into two complete shingle strips. Fig. 3 represents a view showing a series of shingle strips as laid upon a roof.

The same letters of reference indicate the 35 same parts in all the figures.

A shingle strip made by practicing my improved method is composed of a suitable flexible waterproof material in the form of an elongated, flexible strip *a* having trans- 40 verse slots or notches *b* bisecting one edge of the strip and extending therefrom partly across the strip, the length of the slots being sufficient to extend across the portion of the strip which is exposed when the strip 45 is laid. The slots are substantially parallel with each other, and the edges of each slot are substantially parallel. The slots and the edge of the strip bisected thereby, extending across the exposed surface of the 50 strip, form the abutting or opposed edges 2 2 and the lower ends 3 of a series of shingles. The opposite edge portion 4 of

the strip, which in place on a roof is covered and concealed by a strip above it, is continuous, and connects the said shingles as 55 shown in Figs. 2 and 3. When a plurality of strips are laid upon a roof, as indicated in Fig. 3, the slotted portion of each strip overlaps the connecting portion 4 of the next strip below it, so that the connecting 60 portions of the strips are concealed, and the assemblage of strips gives the effect of an ordinary shingled roof, the exposed portion of each strip presenting the appearance of 65 a course of shingles.

My improved method of making the strips *a* is as follows: Taking a sheet *a'* of twice the width of one of the strips *a*, I form between the longitudinal edges thereof, transverse slots *b'*, the ends of the slots being between 70 the edges of the sheet so that both longitudinal edges are continuous. I then subdivide the sheet longitudinally between the ends of the slots along the dotted line 5—5, thus forming the elongated lower ends 3 of two 75 shingle strips, as indicated in Fig. 2. By this method I am enabled to produce the described shingle strips rapidly and economically. The sheet *a'* with its transverse slots *b'* constitutes a shingle strip blank, which is 80 the result of the first step in the method hereinbefore described, and is adapted to be converted into two complete shingle strips by the second step of said method, which involves only the simple operation of making 85 a straight longitudinal cut between the ends of the slots. The said blank may be put on the market as an article of manufacture, and may be converted into complete strips by the user, no special mechanism being required to 90 form the longitudinal cut. The blank may be rolled to form a compact package for transportation and storage.

I claim:

1. A shingle strip blank composed of an 95 elongated sheet of flexible waterproof material, having transverse slots between its edges, the ends of the slots being between the edges of the sheet so that said edges are continuous, said blank being adapted to be 100 converted into two operative shingle strips by severing it lengthwise between the ends of the slots.

2. A shingle strip blank of indeterminate

length composed of an elongated sheet of flexible waterproof material, having transverse slots between its edges, the ends of the slots being between the edges of the sheet so that said edges are continuous, said blank being adapted to be converted into two operative shingle strips of either the full length of the blank or of lesser length by

severing it lengthwise between the ends of the slots.

In testimony whereof I have affixed my signature, in presence of two witnesses.

FREDERICK C. OVERBURY.
